[57] CLAIM

The ornamental design for a template organizer stand, as shown and described.

DESCRIPTION

FIG. 1 is a left side elevational view of a template organizer stand showing my new design;

FIG. 2 is a top plan view thereof;

FIG. 3 is an end elevational view taken from the line 3—3 of FIG. 2;

FIG. 4 is an end elevational view taken from line 4—4 of FIG. 2; and

FIG. 5 is a bottom plan view thereof.
